UNITED STATES PATENT OFFICE

FRANK HUMER, OF DETROIT, MICHIGAN, ASSIGNEE TO GENERAL MOTORS CORPORATION, OF DETROIT, MICHIGAN, A CORPORATION OF DELAWARE

COLLAPSIBLE BOW CONSTRUCTION FOR AN AUTOMOTIVE VEHICLE

Application filed February 14, 1930. Serial No. 428,282.

This invention relates to a collapsible bow construction for an automotive vehicle.

This invention is more particularly concerned with that type of collapsible bow construction in which the bow construction, if normally collapsed, the same would project rearwardly an undesirable distance; for example, in the roadster the bow construction would project rearwardly over the rear deck.

It is an object of this invention to produce a collapsible bow construction in which suitable means are provided for automatically drawing the bow construction forwardly while it is being collapsed to bring the bow construction to the desired position forward of the normal position to which the bow construction would fall were it collapsed without being drawn forward.

It is a further object of this invention to produce a center bow and top rail construction of such a nature that in the collapsed position the side rails will fit within the said center bow.

In the drawings:

Fig. 1 is a side elevation with part of the canopy broken away showing the collapsible bow construction in raised position.

Fig. 2 is a fragmentary plan view of the collapsible bow construction in raised position.

Fig. 3 is a side elevation showing the bow construction partially collapsed.

Fig. 4 is a detail showing the bow construction fully collapsed.

Fig. 5 is a section along the line 5—5 of Fig. 1.

Fig. 6 is a section along the line 6—6 of Fig. 2.

Referring more particularly to the drawings in which I have shown my collapsible bow construction as applied to a roadster although it is understood that this type of collapsible bow construction can be equally well used on other types of vehicles, the cowl may be designated 1, the rear deck 2, the door 3, the windshield pillar 4, and the header bar 5.

The top canopy 6 is arranged to be supported by a collapsible bow construction consisting mainly of the central bow 7, the rear

bow 8, the auxiliary rear bow 9, and the side rails 10.

The side rail 10 consists of the two sections 10a and 10b pivotally connected to each other as at 11 and pivotally mounted on the central bow 7 as at 12. By referring to Fig. 2 it will be seen that section 10b is offset from section 10a; this is to permit the pivotal mounting therebetween of the link 13. The section 10b of the side roof rail is offset from the section 10a for the further purpose of permitting the side roof rail 10 to be telescoped within the central bow 7 when the top is collapsed. The link 13 is pivotally connected to the rod 10a as at 14 and to the center bow 7 as at 15. The joints 11 and 12 are not lock joints but, as is nicely brought out in Figs. 1 and 2, when the rail sections 10a and 10b are in open position the link 13 engages the pivot 11 which firmly holds the sections 10a and 10b in extended position by a cantilever action.

When it is desired to collapse the top the section 10a of the side rail is pivoted upwardly which causes the section 10b to pivot downwardly about the pivot 12 and consequently permits the link 13 to pivot downwardly about the pivot 15 so that the sections 10a and 10b and the link 13 can be collapsed and positioned substantially within the central bow 7.

The central bow 7 is pivotally connected to the body as at 20. The central bow 7 is maintained in upright position by the collapsible brace 21 which is pivotally connected to the central bow 7 as at 22 and to the body as at 23. The collapsible brace 21 is provided with a suitable lock joint 23 which permits it to be collapsed downwardly only as shown in the dotted lines (Fig. 3).

The rear bow 8 consists of two sections 24 and 25 which are connected by the lock joint 26. The section 24 of the rear bow 8 has pivotally mounted thereupon the auxiliary rear bow 9 as at 27. Section 25 of the rear bow 8 is pivotally mounted as at 28 upon a suitable bracket 29 carried by the body. The section 25 is angular as shown by the drawings and has one end connected to the center bow 7 by the link 30 which is pivotally connected

to the section 25 as at 31 and to the center bow as at 32.

When the top 6 is in raised position it may be collapsed as follows:

5 The forward portion of the top 6 is disconnected from the header bar 5. The section 10a of the side rail is pivoted in a clockwise direction about the pivot 11 which in turn causes the section 10b and link 13 to pivot
10 in a counterclockwise direction about the pivots 12 and 15 respectively which in turn collapses the side rail 10 and link 13 so that they fit within the central bow 7. After this has been done the central bow 7 is pivoted rearwardly in a clockwise direction about the pivot 20 and at the same time the collapsible brace 21 is collapsed inwardly and downwardly. As the central bow 7 moves in a clockwise direction about the pivot 20 it in turn, 15 through the link 30, causes the angular section 25 of the rear bow 8 to pivot in a counterclockwise direction about the pivot 28 of the supporting brace 29. This in turn causes the lock joint 26 and the pivot 27 to be rotated 20 in a counter-clockwise direction about the pivot 28 and in turn moves the rear bow section 24 and auxiliary bow 9 forwardly or to the left as viewed in Fig. 1. The desirability of this forward movement of the rear bows 25 30 and 24 is obvious when one considers that if the bow sections 24 and 25 of the rear bow 8 were integral and this rear bow 8 in turn were pivoted clockwise about the pivot 28 it would extend over the rear deck 2 which 35 would be undesirable. Hence, as constructed the rear bow 8 and the auxiliary bow 9 are moved forwardly or to the left as shown in Figs. 3 and 4 as the central bow 7 is pivoted clockwise about the pivot 20 to bring the entire bow construction within the nest 34 provided therefor.

It will be noted that while the bow construction is being collapsed that the rear bows 8 and 9 are subjected to two distinct movements; namely, the section 24 of the bow 40 8 and the bow 9 pivot clockwise about the respective pivots 26 and 27. (This may be called the normal collapsing movement of the said bows.) Secondly, the bows, owing 45 to the counter-clockwise rotation of the angular section 25, are moved to the left or forwardly relative to the body. Hence, the invention consists of a collapsible bow construction that is essentially characterized by 50 associating one part of the bow construction with another part of the bow construction so that the normal collapsing movement of the one part of the bow construction causes, not only a normal collapsing movement of 55 the other part of the bow construction, but an additional or secondary movement of that part of the bow construction relative to the body of the vehicle.

What I claim is:

65 1. A collapsible bow construction for an

automotive vehicle comprising in combination a forward bow pivotally mounted on the vehicle body, a rear bow comprising two pivotally connected sections the lower of which is pivotally mounted on the vehicle body, a link pivotally connecting the forward bow with the lower section of the rear bow forwardly of the pivot connection of the lower section of the rear bow with the vehicle body, and a brace comprising two sections having a lock joint, one section of the brace being pivotally connected to the front bow and the other section being pivotally connected to the vehicle body whereby when the said brace is collapsed the front bow pivots rearwardly toward collapsed position and automatically through the link connection with the rear bow simultaneously collapses and draws the rear bow forwardly. 70 75 80 85

2. A collapsible bow construction for an automotive vehicle arranged to be collapsed within the confine of a well provided therefor in the vehicle body comprising in combination of a forward bow pivotally mounted to the vehicle body, a rear bow comprising an upper section and a lower section pivoted together with a lock joint, the lower section of the rear bow being pivoted to the vehicle body intermediate its ends and having a portion projecting forwardly from the said pivot, a link pivotally connecting the forwardly projecting end of the lower section of the rear bow with the lower portion of the forward bow, and a multiple sectioned brace with a lock joint pivotally connected at one end to the forward bow and at the other end to the vehicle body whereby the said brace can be collapsed to automatically collapse the forward bow and through the connecting link simultaneously collapse and draw the rear bow forwardly to nest the entire collapsible bow construction within the well provided therefor. 90 95 100 105 110

In testimony whereof I affix my signature.

FRANK HUMER.
